CLOCK OR SIMILAR ARTICLE

Mark Wallach, 220 E. 63rd St.,
New York, N.Y. 10021

Filed Feb. 8, 1972, Ser. No. 224,646

Term of patent 14 years

Int. Cl. D10—01

U.S. Cl. D10—26

FIG. 1 is a front elevational view of a clock or similar article showing my new design;

FIG. 2 is a side elevational view thereof;

FIG. 3 is a top plan view thereof;

FIG. 4 is a bottom plan view thereof;

FIG. 5 is a rear elevational view thereof and the transparently shaded rectangle above the battery opening contains the clock movement;

FIG. 6 is a rear elevational view of another embodiment of the design of FIG. 1 wherein the rear panel is plain and unornamented.

I claim:

The ornamental design for a clock or similar article, as shown and described.
